MECHANICAL TOY

Samuel I. Berger, Newark, N. J.

Application January 8, 1935, Serial No. 823

4 Claims. (Cl. 46—40)

This invention relates to mechanical toys and more particularly to toys of the type in which an object is caused to have a step-by-step movement upwardly.

5 Heretofore, there has been provided a mechanical toy in the form of an object simulating a man climbing a ladder. The toy man is provided with spring mechanism which causes his legs to move in the manner of a person climbing a ladder.

10 Heretofore, it has been customary to provide the upper ends of the ladder with notches to receive the prongs of the arms of the toy man when it reached the top of the ladder, holding the toy in that position until the toy was manually released and manually returned to the foot of the ladder.

15 It is therefore, an object of this invention to provide in a mechanical toy of the type simulating a man climbing a ladder, means to cause the toy man, when he has reached a position near the top of the ladder, to automatically return to a position near the lower part of the ladder to start climbing again without requiring any attention whatever, the continued climbing of 20 the toy man depending upon the extent to which the spring mechanism has been wound.

25 A further object of my invention is to provide a toy man and ladder having cooperative means whereby after the toy man has been wound up 30 and begun its initial ascent of the ladder, no further attention need be given to the toy as it will continue to climb the ladder up to a certain point, and then will automatically drop back to its starting point and will repeat this operation 35 until the spring actuating mechanism has become unwound.

30 These and other advantageous objects, which will later appear, are accomplished by the simple and practical construction and arrangement of 40 parts hereinafter described and exhibited in the accompanying drawing, forming part hereof, and in which:

45 Fig. 1 is a perspective view of a toy embodying my invention, and

50 Fig. 2 is a fragmentary vertical cross-sectional view of the filled-in portion and adjacent rounds of the ladder, showing, fragmentarily, the foot of the toy man striking the filled-in portion of the ladder.

55 Referring to the drawing, in Fig. 1 the toy device is shown to comprise a miniature ladder 1 having a plurality of rounds 2. The ladder 1 is preferably pivotally mounted at 3 on a bar 4 secured to the wire base 5; the ladder is preferably supported in an inclined position by means

of the braces 6 which are also secured to the base 5.

The object 7, the representation of a toy man, is provided with arms 8, the extremities of which have prongs 9 which embrace the sides of the ladder and hold the object 7 in position thereon. The legs 10 of the object 7 are designed to engage the rounds 2 of the ladder and in the body of the object 7 there is provided a spring mechanism for moving the legs up and down to simulate the climbing movement of a person climbing a ladder. Key means 11 are provided for winding the spring mechanism (not shown) in the body of the object 7.

10 The above mentioned structure is more or less well known in the art and no claim is made thereto.

15 When the toy man 7 is wound and placed in position near the foot of the ladder, it would ordinarily continue climbing until it reaches the 20 top of the ladder.

25 In accordance with my invention, at a point somewhat near the top of the ladder, the space between two adjacent rounds is filled in at 12 so that when the feet of the man 6 reaches the 30 blank 12, there will be no round upon which the feet can rest, and the step-by-step upward movement of the object will be arrested, causing the object 7 to fall by gravity toward the foot of the ladder. At a point substantially the height 35 of the object 7 and spaced from the foot of the ladder, lugs 13 are provided to be engaged by the prongs 9 of the arms of the object 7, to limit the downward movement of the object.

30 In operation, the spring mechanism in the body 35 of the object 7 is wound by means of the key 11 and the object is started on its upward climbing movement which it maintains until the feet of the object 7 reach the blank 12 between adjacent ladder rounds 2, when the feet of object 7 will 40 automatically become disengaged from the rounds 2 and the object will fall by gravity until the prongs 9 engage the lugs 13. If the spring mechanism has been sufficiently wound, the object 7 will automatically recommence its upward 45 climbing movement without any further attention whatever; and such movement will continue over and over again as long as the spring mechanism is wound.

50 From the above description it will be seen that there has been provided a simple expedient for automatically causing a mechanical toy, such as an object simulating a painter, worker, or the like, climbing a ladder, to automatically repeat its climbing movement without outside attention. 55

This feature makes the operation of the toy automatical while it is wound up.

The foregoing disclosure is to be regarded as descriptive and illustrative only, and not as restrictive or limitative of the invention, of which obviously an embodiment may be constructed including many modifications without departing from the general scope herein indicated and denoted in the appended claims.

10 Having thus described my invention, what I claim as new and desire to secure by Letters Patent, is:

15 1. In a toy device, an inclined ladder having a plurality of spaced rounds, an object successively engaging the rounds of the ladder to simulate climbing movement, and means on the ladder to cause said object to become disengaged from said rounds, so that the object will fall to the foot of the ladder.

20 2. In a toy device, an inclined ladder having a plurality of spaced rounds, an object successively engaging the rounds of the ladder to simulate climbing movement, means on the ladder to cause said object to become disengaged from

said rounds, so that the object will fall to the foot of the ladder, and means on the ladder to limit the downward movement of the object.

3. In a toy device, an inclined ladder having a plurality of spaced rounds, an object successively engaging the rounds of the ladder to simulate climbing movement, said ladder having the space between a pair of adjacent rounds near its top filled in so that when the object reaches that point it will be disengaged from the rounds and fall by gravity to a position near the foot of the ladder.

4. In a toy device, an inclined ladder having a plurality of spaced rounds, an object successively engaging the rounds of the ladder to simulate climbing movement, said ladder having the space between a pair of adjacent rounds near its top filled in so that when the object reaches that point it will be disengaged from the rounds and fall by gravity to a position near the foot of the ladder, and means on the ladder adjacent the foot thereof to limit the downward movement of the object.

SAMUEL I. BERGER.
